UNITED STATES PATENT OFFICE.

ANDRÉ F. GOBIN, OF NEW YORK, N. Y.

RAILROAD-SPIKE.

1,075,911.

Specification of Letters Patent. Patented Oct. 14, 1913.

Application filed January 22, 1913. Serial No. 743,468.

To all whom it may concern:

Be it known that I, ANDRÉ F. GOBIN, a citizen of the United States, and a resident of the city of New York, borough of Brooklyn, in the county of Kings and State of New York, have invented a new and Improved Railroad-Spike, of which the following is a full, clear, and exact description.

Among the principal objects which the present invention has in view are: To provide a spike of the character named having means for receiving an extraneous device, operative to connect the spike with the material in which it is driven, at a point below the surface of said material; to provide a spike of the character named, having means for preventing axial movement, or twisting of the same when driven; and to provide a spike of the character named, wherein the body section is constructed to conform with the conventional spike of the class indicated.

One embodiment of the present invention is shown in the accompanying drawings, in which—

25 Figure 1 is an edge view of a spike constructed and arranged in accordance with the present invention, having shown in conjunction therewith a fragment of a railroad tie in which the spike is driven, a fragment 30 of the railroad rail flange, and an anchoring staple for said spike prior to being driven therein; Fig. 2 is a side view of a spike constructed and arranged in accordance with the present invention, shown in 35 conjunction with the railroad tie and anchoring staple, said staple being shown in driven position, and a fragment of the spike being cut away to show the formation of the hole for receiving the anchoring staple; 40 Fig. 3 is a top view of a spike constructed and arranged in accordance with the present invention.

As seen in the accompanying drawings, the body portion 8 is shaped to conform with 45 the conventional railway spike, having a head 9 and a wedge-point 10. The body portion 8 is provided with side fins 11, which terminate at the lower end in wedge ends 12 arranged, as seen in the drawings, 50 to die into the edges of the body portion. The outer edges of the fins 11 are curved, as seen best in Fig. 3 of the drawings, the curvature of the sides being concentric with holes 13 which are bored into said fins 55 through the head 9 to form passages for the

sides of the staple 14. At their lower ends the holes 13 are outwardly inclined, to form an inclined wall 15, which operates to deflect outwardly the sharpened ends 16 of the staple 14 when said staple is driven downward through the holes 13.

In operation, the spike herein described is handled much in the same manner as the conventional spike. It is driven into a tie A in the same manner as is the conventional spike. After the point 10 and part of the body portion 8 has been embedded in the wood of the tie, the wedge ends 12 of the fins 11 are introduced, the fins 11 thereafter entering into the structure of the tie in the manner as seen in Fig. 2 of the drawings. When the head 9 of the spike is driven to rest on the flange B, the staple 14 is introduced, the ledge thereof entering the holes 13 formed in the fins 11. The staple is now driven down through the holes 13 until the points 16 thereof strike upon the inclined walls 15 and are deflected outward from the spike to enter the wood of the tie A. The continued pressure of the inclined wall against the side of the staple curls the ends of the staple in the manner substantially as shown in Fig. 2 of the drawings. When the staple is driven home so that the cross head bar thereof rests upon the head 9 of the spike, it will be seen that the combined spike and staple are in a position which renders it difficult if not impossible, to lift the same out of the tie A. It is obvious that the resistance of the fins 11 prevents the possibility of twisting or turning the spike upon its longitudinal center during the driving of the staple or at any other time. It is equally obvious that after the staple has been driven, the outwardly-extended ends thereof cooperate with the fins 11 to prevent the distortion or displacement of said spike.

Having thus described my invention, I claim as new and desire to secure by Letters Patent:—

1. A railway spike, comprising a conventionally-shaped body portion having integrally-formed laterally-extending fins, said fins having lengthwise passages open at both ends and terminating at the bottom with outwardly-inclined walls.

2. A railway spike, comprising a conventionally-shaped body portion having integrally-formed laterally-extending fins, said

- 5 fins having lengthwise passages open at both ends and terminating at the bottom with outwardly-inclined walls, and said fins being further provided with wedge-shaped 5 solid terminals extending below said inclined walls.
- 10 3. A railway spike, comprising a conventionally-shaped body portion having integrally-formed laterally-extending fins, said 10 fins having lengthwise passages open at both ends and terminating at the bottom with outwardly-inclined walls, said fins having a lesser transverse dimension than said body portion.
- 15 4. A railway spike, comprising a conventionally-shaped body portion; two oppositely-disposed and laterally extending fins, said fins being integrally formed with said body portion and having open-ended 15 passages formed therein; and means formed on said body portion, extending across the path of said passages, to deflect the material through which the spike is driven, from entering said passages.
- 20 5. A railway spike, comprising a conventionally-shaped body portion having integrally-formed laterally-extending fins, said 20 fins having lengthwise passages open at both ends and terminating at the bottom with outwardly-inclined walls; and bendable fas-

tening devices extending through said passages and laterally from the bottom thereof.

6. A railway spike, comprising a conventionally-shaped body portion having integrally-formed laterally-extending fins, said 35 fins having lengthwise passages open at both ends and terminating at the bottom with outwardly-inclined walls; and a staple having legs extending through said passages and curled outward from the lower end 40 thereof.

7. A railway spike, having a body portion the end whereof is wedge-shaped having sides substantially parallel, said body portion being provided with laterally-extending 45 fins disposed substantially parallel to the longitudinal axis of said body portion, each of said fins having a lengthwise passage extended therethrough and open at both ends thereof; and means disposed at the lower 50 end of each of said passages for deflecting a nail-like device driven therethrough.

In testimony whereof I have signed my name to this specification in the presence of two subscribing witnesses.

ANDRÉ F. GOBIN.
